UNITED STATES PATENT OFFICE.

JOSEPH L. CLINGMAN, OF CYNTHIANA, KENTUCKY.

NUT-LOCK FOR RAIL-JOINTS.

SPECIFICATION forming part of Letters Patent No. 273,029, dated February 27, 1883.

Application filed December 16, 1882. (Model.)

To all whom it may concern:

Be it known that I, JOSEPH L. CLINGMAN, of Cynthiana, in the county of Harrison and State of Kentucky, have invented a new and Improved Nut-Lock for Rail-Joints, of which the following is a full, clear, and exact description.

My invention consists of a plate secured by the bolts and nuts, and having loops formed in it, by which a split key or equivalent device is made to secure a locking-plate having forked or notched ends that bear against the nuts of the joint-bolts and prevent them from turning, the contrivance being very simple and cheap to make, and being calculated to afford substantial and permanent security to the nuts, at the same time being capable of removal and reapplication without damage to any of the parts, all as hereinafter fully described.

Reference is to be had to the accompanying drawings, forming a part of this specification, in which similar letters of reference indicate corresponding parts in all the figures.

Figure 1 is a side elevation of a rail-joint with my improved nut-lock attached. Fig. 2 is a horizontal section of Fig. 1 on line xx . Fig. 3 is a transverse section on line yy . Fig. 4 is an elevation of the notched plate. Fig. 5 is a perspective view of the key, and Fig. 6 is a perspective view of a portion of the looped plate by which the locking-plate is secured.

In the first place, I apply a plate, a , having loops b at the middle, or thereabout, to the bolts c , and secure it by the nuts d firmly against the side of the joint-plate e . I then apply a locking-plate, f , having notched or forked ends g and notches h , to the said looped plate, and then secure said plates together by

a split or bent spring-key, i , passed through the loops b , around or outside of plate f , thus firmly securing the locking-plate, which, by its notches g fitting the sides of the nuts, securely fastens them against turning loose. I prefer to make the loop-plate by punching out a portion at j , forming a slot as long as or a little longer than the loops are to be, and then bending up the loops, as shown, said loops being thus made a suitable distance apart for the narrow portion k of the locking-plate to drop in between them. I propose to make the lower prongs, m , of the locking-plate to extend down sufficiently to bear on the base n of the joint-plate or rail for resting thereon, making them longer than the upper prongs, if required.

Having thus described my invention, I claim as new and desire to secure by Letters Patent—

1. In a nut-lock for rail-joints, a plate, a , having loops b , slot j , and holes for the joint-bolts, and being secured to the side of the joint-plate by the joint bolts and nuts, substantially as described.

2. In a nut-lock for rail-joints, a forked or flanged plate, f , having notches h , and being secured to the looped plate by a key, i , substantially as described.

3. In a nut-lock, the combination, with the joint bolts and nuts and the plate a , having loops b , slot j , and holes for the joint-bolts, of the forked plate f , having notches h , and key i , substantially as described, and for the purpose set forth.

JOSEPH L. CLINGMAN.
